UNITED STATES PATENT OFFICE

IRA D. FORD, OF ROSELAND, ONTARIO, CANADA, ASSIGNOR TO UNIVERSAL BUTTON FASTENING & BUTTON COMPANY, OF DETROIT, MICHIGAN, A CORPORATION OF MICHIGAN

BUTTON

Application filed August 4, 1930. Serial No. 472,844.

This invention relates to buttons of the ring coat-button type and among other objects aims to provide an improved button better adapted for automatic machine attachment and which may be manufactured at a relatively low cost.

The nature of the invention may be readily understood by referring to one illustrative button embodying the invention and illustrated in the accompanying drawing.

In said drawing:

Fig. 1 is a sectional elevation of the button.

Fig. 2 is a plan view of the button with the top or shell removed, and

Fig. 3 is a bottom plan view from the plane 3—3 of Fig. 1.

The attachment of ring buttons at the place of manufacture of the garment is preferably effected by automatic machinery for obvious reasons, notwithstanding the fact that later buttons may be detached and reattached by hand for purposes of laundering. The ring coat type of button involves a number of problems not encountered in other types of button, such for example as provision of adequate strength to prevent mutilation in the automatic attaching operation and in other handling or treatment to which the button may be subjected, such as the inadvertent passing through laundry apparatus, and the necessity of uniformity in position of the eye or ring of the button to insure reliable operation in the attaching machine. These and other qualities are embodied in the illustrative button as will be apparent from the following description.

The illustrative button generally comprises a head in the form of a sheet metal shell 10 and an eye 11 attached thereto with sufficient firmness and rigidity to insure the maintenance of its perpendicular position relative to the back of the button during the passage through the automatic attaching machine. The eye 11, in this instance, is made from adequately stiff wire bent into U-shape with its ends 12 bent so as to lie against the underface of the button head.

The ring or eye in this case is attached to the button by means of a back member 13,

in this case of sheet metal, formed to correspond substantially with the underface of the rounded button head. The extremities of the wire forming the eye pass through an elongated slot 14 (of a size adequate to admit both legs of the wire eye when lying closely together) pierced substantially in the center of the back member 13. The back member is advantageously depressed or offset as at 15 to provide a recess for the extremities 12 of the eye 11, such extremities being firmly clamped between the button top and the back member.

After the eye is applied to the back member, the burrs 16 comprising the metal pierced inwardly in forming the slotted opening 14 are pressed downwardly upon or around portions of the wire which project through the slot, so as temporarily to hold the eye against displacement in handling and assembly of the button, that is, until after the back member 13 and the button top are assembled and united. After assembly, movement of the eye relative to the button is prevented by the firm clamping of the extremities 12 between the back 13 and top 10.

Union of the back member 13 and top 10 is effected in the present instance by turning or curling over their respective margins 17 and 18 after the back 13 has been nested inside the top 10. This operation is advantageously performed by a die which thus insures absolute uniformity of external diameter of the button, a feature which is very important in attachment by machine. The bead thus formed (see Fig. 1) serves not only to hold the button parts together firmly but to provide a nicely rounded edge on the button which gives the button a substantial appearance.

The ends 12 of the eye are in this instance somewhat longer than the distance of the center of the recess 15 to its edge and are therefore curled or bent (see Fig. 2) around the inside of the circular wall of the recess. The additional length of wire in the aforesaid extremities contributes to the firmness with which the eye is clamped between the button top and back 13.

In addition to the strength against

crushing contributed by the arched or convex shape of the button top and back member 13, the latter may advantageously be reinforced as at 17 by radial grooves, ribs or corrugations, which in addition have a decorative effect (simulating a sunburst design) which contributes to the selling quality of the button.

The concave underface of the button resulting in this instance from the convex top and the nesting of the top and back members together, provides a space for the attachment of the eye to the button without increasing its thickness for that purpose alone, and results in causing the button to hug the cloth closely and not stand away from the cloth as do buttons with flat backs. This substantially contributes to the neat appearance of the button in use on the garment.

It is apparent from the foregoing that the number of separate elements of the button have been reduced to a minimum while at the same time securing all the advantages of strength possessed by buttons made of a larger number of elements, and the construction is such as to insure uniformity of dimensions and stability in the position of the eye. The cost of the button as regards both the cost of individual parts as well as the cost of assembly has been substantially reduced.

The button may of course be superficially decorated by any appropriate coating or plating, and the top may also be embossed with a decorative design or trademark depending upon the wishes of the purchaser.

Obviously the invention is not limited to the details of the illustrative embodiment since these may be variously modified. Moreover it is not indispensable that all features of the invention be used conjointly since certain features may advantageously be employed in different combinations and sub-combinations.

Having described my invention, I claim:

1. A button of the character described comprising in combination, a wire loop forming an eye and having an attaching extremity, a metal top and a sheet metal back member, said top and back member conforming in shape so that said back member nests inside said top and being formed to provide a central recess in which said extremity is seated, said recess being only deep enough to receive said extremity, the margins of said top and back member being curled together to hold the same together and to clamp said extremity firmly between the top and back member.
2. A metal button of the character described comprising in combination, a sheet metal button top, a wire button eye having the ends of the wire bent at an angle to the plane of the eye to provide an attaching extremity, and a sheet metal back member having a recess in which said extremity is seated, said recess being only deep enough to receive

said extremity, the margin of said top being curled downwardly over the margin of said back member to hold the latter in place.

3. A button of the character described comprising in combination, a convex sheet metal top, a sheet metal back member having a central recess therein, and an eye projecting from said back member and having extremities passing through said back member and being seated in said recess, said back member being in contact with the underface of said top and clamping said extremities in said recess against said button top, said recess being only deep enough to receive said extremities, whereby the latter are firmly held between said top and said back member.

4. A button of the character described comprising in combination, a button top, a button eye having attaching extremities, and a back member having an opening through which said eye passes engaging said attaching extremities and clamping the same firmly against said top.

5. A button of the character described comprising in combination, a sheet metal button top, a button eye having an attaching extremity, and a sheet metal back member having radial reinforcing ribs seated inside said top and engaging said extremities.

6. A button of the character described comprising in combination, a sheet metal button top, a button eye having an attaching extremity, and a sheet metal back member having radial reinforcing ribs seated inside said top and engaging said extremities, the margin of said top being curled downwardly over the margin of said back member to hold the latter in place.

In witness of the foregoing I affix my signature.

IRA D. FORD.
